TOTE BOX

Arthur H. Eichholz, Polo, Ill., assignor to Central Stamping & Mfg. Co., Polo, Ill., a corporation of Illinois

Application November 1, 1957, Serial No. 693,995

3 Claims. (Cl. 206—16)

This invention is directed to a new and improved utility case for carrying tools.

One purpose of the present invention is to provide a carrying case for tools which allows division of the case into separate tool carrying sections.

Another purpose of the present invention is to provide a tool carrying case with improved means for holding tools or articles in the case.

Another purpose of the present invention is the provision of a tool carrying case that is easily formed and manufactured.

Another purpose of the present invention is the provision of an improved tool carrying case with a top wall that functions not only as a cover for the case but also as a holding structure for tools positioned in the case.

Other purposes of the invention will appear from time to time in the course of the ensuing specification and claims.

Referring generally to the drawings:

Figure 1 is a side elevation of the improved case;

Figure 2 is an end elevation of the case shown in Figure 1;

Figure 3 is a sectional view taken along the sectional lines of Figure 1;

Figure 4 is a plan view of the case shown in Figure 1;

Figure 5 is a sectional view taken along the sectional lines of Figure 4 and illustrating a portion of the case.

Like elements are designated by like characters throughout the specification and drawings.

Referring specifically now to the drawings and in the first instance to Figure 1, the numeral 1 refers to a carrying case body which may be formed from a folded metal stamping. The case 1, which forms the lower section of a two section assembly, may have a bottom wall 2, side walls 3 and 4, and end walls 5 and 6. Dimples 7 may be formed in the bottom of the case to provide depending projections upon which the case may rest.

The other section of the case is comprised of a top generally designated as 8. According to the invention, the top 8 has a bottom wall 9 which serves both as a cover for the space within the lower section 1 and as a bottom wall for a carrying tray which is comprised of the upper or top section. The top has side walls 10 and 11 which are secured to and upstanding from the bottom wall 9. The upper portions of the side walls 10 and 11 may be curved inwardly toward the center of the top to provide overhanging retaining ledges for articles disposed in the upper section. The top has end walls 12 and 13 joined to the side walls.

The top section may be detachably and removably secured to the bottom case section 1 as through the use of any suitable clasps generally designated at 14 and 15. The top section may have a depending rim 16 adapted to snugly fit over an upstanding rim 17 on the lower section.

An upstanding member is formed in the bottom wall 9 of the upper section. This member is designated at 18

2

and may be drawn from the metallic bottom wall 9 of the upper section. As is seen best in Figure 5 the member 18 is generally rectangular in cross section. It defines a space 19 which is exposed to the interior of the lower case section 1. A handle 20 extends longitudinally of the upper section 8 and may be fixed to the interior of the end walls 12 and 13 and also secured to the upstanding member 18. The upper portion of the handle is disposed above the level of the upper portion of the side walls 10 and 11. The ends of the member 18 may have tab portions 21, 22, and 23 folded inwardly therefrom and welded to the end walls 12 and 13 of the upper section, to add rigidity to the member 18, handle 20, end walls 12 and 13, and bottom 9.

An inclined shelf 24 is positioned within the lower section 1 and provides an inclined surface 25 extending longitudinally of the lower section and offset with respect to the longitudinal center line of the upper section 8 and lower section 1. The surface 25 is, however, disposed beneath the open space 19 in the upper section 8. The shelf may have depending legs 26 and 27 which are welded to the bottom wall 2 of the lower section in order to position the shelf illustrated in the position of Figure 3. The lower end of the shelf may have an upstanding ledge 28 to provide a stop against which tools or other articles may rest. The ledge 28 may have a retaining ledge portion 28a extending parallel to the direction of surface 25.

A bracket 29, which is generally U-shaped in form, has the legs thereof fixed to one end wall 6 of the lower section. The medial portion of the bracket 29 is positioned a small distance from the end wall to provide a space within which tools may be disposed and held by the bracket 29. A cushioning pad, which may be formed from a felt strip 30, is positioned beneath the bracket. It may be adhesively secured to the bottom wall 2 of the lower section.

A rubber pad 31 is attached to the inner surface of the member 18 to provide resilient gripping surfaces on opposite sides of the opening 19.

Whereas I have shown an operative form of the invention, I wish it to be understood that the showing and description thereof should be taken in an illustrative or diagrammatic sense only. There are many modifications 45 which will fall within the spirit and scope of the invention and which will be apparent to those skilled in the art. The scope of the invention is to be limited only by the scope of the hereinafter appended claims.

The use and operation of the invention are as follows: 50 I illustrate a carrying case for carpenters' or electricians' tools. This type of case is commonly referred to as a "Tote" box. The invention contemplates a carrying case which is formed of two separable, tool carrying sections, with an upper section providing both a cover for the lower section and a carrying tray for tools. Thus the workman on the job may dispose a small number of the tools carried by the case in the upper section or tray. The workman is thus able to leave the lower section with the majority of tools therein in one locale while he carries the tray or upper section with him on the job. The upper section is more easily handled than the overall case, and the overall weight that the workman is required to carry as he moves from spot to spot on the job is considerably less than that required in moving the entire case.

The case contemplates the advantageous use of a handle portion in the tray which is so formed as to rigidify the tray while at the same time providing a novel means of securing tools in the lower section. A saw blade may, for example, be disposed on the surface 25 of the shelf 24 with its handle extending in an upward direction and with the lower end of the saw positioned against the retaining ledge 28a. The handle of the saw may extend up-

wardly into the open space in the member 18 where it is resiliently and removably held in position by the rubber clamping strip 31. Thus in the assembled position of the two sections, the upper section serves to hold tools in place within the lower section.

The ledge is so formed that it disposes tools held by the member 18 in an upper position with respect to the bottom wall 2 of the lower section. Other tools may be loosely disposed within the lower section, and the disposition of the shelf prevents damaging contact between such loosely disposed tools and tools held by the member 18.

When it is desired to transport the entire assembly, the upper section is secured to the lower section by the clasps 14 and 15 and the workman lifts and carries the entire assembly with the handle 20. When only the upper section is needed for transport, the clasps 14 and 15 are detached, thus allowing the workman to leave the lower section in a fixed position, while he carries the upper section tray on the job.

Whereas one form of the lower case section is illustrated in the drawings and described in this specification, it should be understood that this lower section is to be taken as illustrative or in a diagrammatic sense, as illustrating a typical lower case section with which the upper case section may be associated. The lower case section 25 may take any one of several well known forms.

I claim:

1. A container for tools of various sizes and configura-

tions including a metallic container body and having defined side, end, and bottom walls, a removable top for said container, said top providing a tray defined by side and end walls upstanding from a bottom wall, said last named bottom wall overlying and covering said container, and a handle upstanding from said last named bottom wall, said handle being secured to an upstanding member formed on said bottom wall, said member extending longitudinally of the bottom wall, said member having an opening extending lengthwise thereof and exposed to the interior of the container so as to provide a storage space in said member.

2. The structure of claim 1 characterized by and including gripping means in said upstanding member.

3. The structure of claim 1 wherein a resilient gripping strip is secured to the walls of said opening so as to resiliently grip objects between the walls of said opening.
